[57] **CLAIM**

The ornamental design for a tire, as shown and described.

DESCRIPTION

FIG. 1 is a perspective view of a tire showing my new design, it being understood that the tread design is repeated throughout the circumference of the tire as shown schematically in solid lines, the opposite side being substantially the same as the side shown.

FIG. 2 is an enlarged cross sectional view thereof taken on line 2—2 of FIG. 1.
